No. 777,231.

PATENTED DEC. 13, 1904.

F. A. WERNING & J. STUBBERS.

GLOBE HOLDER.

APPLICATION FILED JUNE 17, 1904.

NO MODEL.

UNITED STATES PATENT OFFICE.

FRANK A. WERNING, OF BELLEVUE, AND JOSEPH STUBBERS, OF COVINGTON, KENTUCKY, ASSIGNORS TO THE INCANDESCENT LIGHT & STOVE COMPANY, OF CINCINNATI, OHIO, A CORPORATION.

GLOBE-HOLDER.

SPECIFICATION forming part of Letters Patent No. 777,231, dated December 13, 1904.

Application filed June 17, 1904. Serial No. 213,010. (No model.)

To all whom it may concern.

Be it known that we, FRANK A. WERNING, residing at Bellevue, in the county of Campbell, and JOSEPH STUBBERS, residing at Covington, in the county of Kenton, State of Kentucky, citizens of the United States, have invented certain new and useful Improvements in Globe-Holders, of which the following is a specification.

10 Our invention relates to a globe-holder for a gas-burner; and it has particular reference to the means for attaching the holder to the burner, and, second, for attaching the globe to the holder.

15 The features of the invention are more fully set forth in the description of the accompanying drawings, forming a part of this specification, in which—

Figure 1 is a side elevation of our globe-holder attached in position and shown partly in section. Fig. 2 is a section on line *xx*, Fig. 1, of the burner with the holder shown in plan. Fig. 3 is a section on line *ww*, Fig. 2, with burner omitted and globe attached.

25 1 represents the burner, from the bottom of which extends the projection 2, a portion of which is substantially rectangular in cross-section, provided with the lugs 3, projecting laterally, upon which the globe-holder seats 30 the projection 2. The projection is less in cross-section than the bottom of the burner from which it extends, so that the bottom of the burner around the projection 2 forms a shoulder.

35 4 represents a globe-holder having a supporting-tray 5 and the sleeve 6. Sleeve 6 is provided with a central orifice 7 large enough to go over the projection 2. Sleeve 6 has the flanges 8, provided with the notches 7, adapted 40 to pass over the lugs 3. (See Fig. 2.) Within the sleeve 6, above the flanges 8 and parallel with the notches 7, are the springs 10.

In attaching the holder the sleeve 6 is placed over the lower end of the projection 2, with 45 the lugs 3 and notches 7 in alinement. The sleeve is then pushed over the projection 2 until the top of the sleeve 6 comes to a bearing against the shoulder 22 and the lugs 3 come

through the notches 7 and under the flanges 8. The holder is then given a slight turn, 50 which brings the flanges 8 above the lugs 3 and places the notches 7 opposite the wider faces of the projection and at right angles relative to the lugs 3. The springs 10 are separated sufficiently to freely pass the projection 2 when the lugs and notches are in alinement; but the springs are separated a distance less the length of the diagonal line of the rectangular cross-section of the projection 2, and hence when the notches in the 60 holder are turned at right angles to the lugs the springs 10 are strained apart by and engage against the narrower faces of the projection 2, exerting sufficient tension thereon to hold the sleeve in place on the burner projection 2.

In order to attach the globe to the tray 5 of the holder, we provide the clamps 11, which are inserted through the tray inside of the flange 12. The lower ends 13 of the clamps 70 are outwardly turned and provided with screw-threaded orifices, through which engage the clamping-screws 14. The upper ends of the clamps are shaped to conform to the interior surface of the globe. The globe 25 is placed 75 on the tray with the clamps 11 inside. The screws 14 are tightened, their outer ends engaging upwardly against the lower surface of the tray 5, exerting a leverage on the clamps, which press the lower ends of the clamps inward and the upper ends of the clamps outward, more or less yieldingly against the inner surface of the globe, the clamps fulcruming against the tray at the orifices 16, through which they are inserted. Obviously this is a 80 substantial means for holding the globe and does not subject the same to any positive impingement, such as a screw engaging with the globe. Further, it enables the use of various sizes of globes, as any globe coming within 85 the radii of the clamps can be secured thereby.

The device is simple and cheap, convenient in use, and effective in operation, and enables a convenient removal of the globe from the burner by a slight turn of the holder and likewise as easily attached.

Having described our invention, we claim—

1. In combination with a burner, a projection from the lower end thereof, a portion of which is substantially rectangular in cross-section, having two sides of less width than the other two sides, lugs projected laterally from the narrower faces of the rectangular portion of said projection, a globe-holder having a sleeve, the upper portion of which seats against the lower end of the burner, the lower portion of the sleeve being provided with notched flanges adapted to pass over the burner projection, and above said lugs when the notches are alined therewith, and to interlock against the under surfaces of the flanges when the holder is turned to bring the notches at right angles to the lugs, and a spring in the sleeve adapted to engage against the projection in said position, substantially as described. 45
2. In combination with a burner, a projection from the lower end thereof, a portion of which is substantially rectangular in cross-section, having two sides of less width than the other two sides, lugs projecting laterally from the narrower faces of the rectangular portion of said projection, the lower end of the burner forming a shoulder above and around the said burner projection, a globe-holder having a central sleeve, the upper portion of which seats against said shoulder, the lower portion of the sleeve being provided with flanges and notches adapted to pass over the projection and above the lugs thereof when the lugs and notches are placed in alinement, the interior 50 of the sleeve being provided with two springs substantially parallel with the notches of the sleeves, the said springs being separated a distance less than the diagonal line of the rectangular cross - section of said projection, whereby when the sleeve is placed on the projection above the lugs, and given a turn, the flanges will interlock with the upper surfaces 55
3. In combination with a burner and globe-holder having a supporting-tray, with an outer peripheral flange, clamps inserted through the tray inside of the flange, having the upper ends bent to conform to the interior surface of the globe to be held, the lower ends of the said clamps under the tray, being outwardly bent, and provided with screw-threaded orifices, screws taking into said orifices and having their upper ends engaging against the under surface of the tray, whereby when said screws are tightened the upper ends of said clamps are expanded, substantially as described. 60
4. In combination with a burner and globe-holder having a supporting-tray, with an outer peripheral flange, clamps inserted through the tray inside of the flange, the opposite ends of the clamps being bent outwardly from the orifices in the tray through which they are inserted, the upper ends of the clamps being shaped to conform to the inner surface of the globe, the lower ends of the clamps below the tray being provided with screw-threaded orifices, clamping-screws engaging upwardly through said orifices and bearing against the under surface of the tray whereby when the said screws are tightened, the upper ends of said clamps will be expanded, substantially as 65 70 75 described.

In testimony whereof we have hereunto set our hands.

FRANK A. WERNING.
JOSEPH STUBBERS.
